UNITED STATES PATENT OFFICE.

RUFUS A. FREEMAN, OF FLUSHING, NEW YORK, ASSIGNOR TO THE AUTOPRESS COMPANY, OF NEW YORK, N. Y., A CORPORATION OF NEW YORK.

PRINTING-MACHINE.

1,252,422.

Specification of Letters Patent.

Patented Jan. 8, 1918.

Application filed May 13, 1913. Serial No. 767,262.

To all whom it may concern:

Be it known that I, RUFUS A. FREEMAN, a citizen of the United States, and a resident of Flushing, in the county of Queens 5 and State of New York, have invented certain new and useful Improvements in Printing-Machines, of which the following is a specification.

My invention relates particularly to devices for the accurate placing of sheets on sheet carriers, especially the impression cylinders of printing machines, and particularly in that type of printing machine in which the impression cylinder both reciprocates and rotates. As is well known in the art, it is necessary, in order to secure register, that successive sheets shall be taken by the sheet-taking means on the sheet carriers of printing machines, so that each sheet will 10 fall exactly in the same place as its predecessor. In machines moving at high speeds, and particularly in machines in which the cylinder has both a rotary and reciprocating motion, this has been extremely difficult 15 to attain, and it is one of the objects of my present invention to provide mechanism by which this may be accomplished.

With these and other objects in view, my invention consists of novel features of construction, combination and arrangement of parts as will be more fully described and pointed out in the appended claims.

In the accompanying drawings, Figure 1 represents a portion of a side sectional elevation of one form of printing machine which I have selected for purposes of illustration, showing my novel sheet taking and sheet gaging mechanism in their positions just before the sheet is taken.

Fig. 2 represents a plan view of a portion of Fig. 1.

Fig. 3 represents a side elevation of a portion of Fig. 2, looking in the direction of the arrows 3—3 of Fig. 2.

Figs. 4, 5, and 6 represent portions of my novel sheet taking and sheet gaging mechanisms, showing the successive positions thereof.

The corresponding parts are referred to both in the drawings and the specification by similar reference characters.

Referring now to Fig. 1, 10 represents a reciprocating form bed of the type of press which I have chosen for purposes of illustration. This form bed 10 carries racks 11

which engage with gears 12 on the ends of an impression cylinder 13. By suitable gearing, not shown but well-known to those skilled in the art, the reciprocation of the bed 10 causes the cylinder 13 to rotate, and at the same time, reciprocate in the guideways 14 on the side frames 15 of the machine. 16 is a sheet feed board of the usual type provided, in the form of press which I have illustrated, with continuously running 60 tapes 17 to carry sheets successively toward sheet gages 18, which are attached to a shaft 19, and are normally held across the plane of a sheet on the feed board 16 by a spring 20, acting against a stop, all in the usual 65 manner. To the end of the shaft 19 is attached a lever 21 provided with an ear 22 carrying an adjusting screw 23. This adjusting screw 23 abuts against a lever 24 pivotally mounted on the shaft 19 and arranged to contact with the screw 23 when the lever 24 is moved to the left of Fig. 3. A cam fork 25 is attached to the lever 24 and carries a cam roll 26 running on a cam 27 mounted on a cam shaft 28, driven 70 through suitable gearing from the mechanism which drives the form bed 10, so that the shaft 28 rotates continuously and in 75 timed relation with the motions of the form bed. The lever 24 is provided also with a 80 beveled sliding block 29, normally held downward by a spring 30 in the lever 24. Attached to the cylinder 13 is a block 31, also beveled, the member 29 being arranged 85 to extend into the path of block 31. 90

Referring now to Figs. 1, 4, 5, and 6, the method of operation of my novel sheet gaging device will be clear. In Figs. 1 and 4, the reciprocating and rotating cylinder 13 is moving to the left with the sheet grippers, 95 hereafter to be described, open, and a sheet placed on the feed board 16, has its edge against the gages 18. The block 31 moves against the beveled member 29 and pushes the latter upward against the pressure of the spring 30, allowing the block 31 to pass. Obviously this does not disturb the position of the gages 18, the motion given to the lever 24 by the block 31, if any, being away from the screw 23, and therefore, not disturbing 100 the shaft 19 or the gages 18 thereon. 105

When the cylinder 13 has reached the end of its motion to the left of Fig. 1, and starts to move toward the right as shown in Figs. 5 and 6, the flat side of the block 31 will 110

contact with the flat side of the sliding member 29, and the lever 24 will, therefore, be moved to the right of Figs. 5 and 6. This carries the lever 24 against the screw 23, which, through the lever 21, swings the shaft 19, and with it the gages 18. Preferably, I proportion the members in such a way that the gages 18 do not start to move until exactly the instant that the sheet grippers referred to, engage the sheet, after which time the gages 18 move at a slightly faster rate than the sheet, so as not to interfere with it. At or before the time when the block 31 passes out of contact with the member 29, the cam 27 will have turned so that its high part is in contact with the roller 26, thus preventing the gages 18 from falling back to their gaging position until after the sheet has passed, which time is determined by the arc of the high part of the cam 27. After the sheet has passed, the roller 26 runs down the cam 27, permitting the gages 18 to move into gaging position through the pressure of the spring 20, ready for the presentation of the next sheet. The screw 23 provides a means by which the relation between the levers 24 and 21 may be regulated, thus positioning the gage shaft 19. In addition, each of the gages 18 is provided with individual adjusting means, in the usual manner.

It is obvious that many other forms of mechanism may be used to enable the gages to be moved by the cylinder as the sheet is being taken and to prevent said gages from being disturbed as the cylinder is moving back toward the sheet. The block 31, may, if desired, be attached to any mechanism directly connected with the cylinder, so that it has at all times a fixed relation with the impression surface thereof, or contact may be made with a portion of the cylinder itself, thus doing away with the block 31. It will be obvious that the gage is swung away from the sheet at exactly the same point of travel of the sheet carrying surface of the cylinder, regardless of any defects in the mechanism by which the cylinder is moved.

The sheet taking means on the cylinder 13 which I have chosen for illustration, are the usual grippers 32 mounted on a shaft 33 to which is attached a cam lever 34 carrying a cam roller 35. The grippers 32 are normally held closed against the cylinder 13 by a spring 36 mounted on a rod 37, which is connected to a pair of toggle links 38, one of which links is attached to the cylinder at 39 and the other of which is connected to a lever 40 attached to the gripper shaft 33. The spring 36 abuts against the member 40 connected to the cylinder and provided with a stem 41, extending into a hollow in the rod 37.

Pivottally connected to the side frame of the machine at 42, is a cam 43 lying in the path of the roller 35, as the cylinder 13 ro-

tates and reciprocates. Connected to the cam 43 is a cam fork 44 carrying a cam roller 45 running on a cam 46 mounted on the shaft 28. The cam 43 is so shaped and the cam 46 is so shaped and timed, that as the cylinder 13 is moving to the left, as shown in Fig. 4, the cam 43 is in the full line position and the grippers 32 are opened and held open as the cylinder is coming to the end of its motion to the left. At about the time when the motion of the cylinder 13 is reversed, the cam roller 45 runs down from the high part of cam 46, thus permitting the cam 43 to swing to the dotted line position of Fig. 4, and the full line position of Figs. 5 and 6. A stop 47 is provided to limit the motion of the cam 43 and to form a fixed abutment to hold the cam 43 in its operative position as the grippers 32 close. Now as the cylinder 13 moves to the right of Figs. 5 and 6, the cam roller 35 runs down the cam 43 and permits the grippers 32 to close on the sheet placed against the gages 18, these gages being arranged, preferably, as I have pointed out before, to swing out of the path of the sheet at the instant the grippers 32 close on it. By the mechanism illustrated for opening and closing the grippers 32, I have provided a means by which the grippers will be held open to clear the edge of the sheet as the cylinder is moving to the left of Figs. 5 and 6, so that the position of the sheet against the gages 18 is in no wise disturbed, and by which the grippers will close by their cam roller running down what is in effect a fixed cam at the time such closing takes place, so that the grippers will close on each sheet at identically the same spot irrespective of the position and amount of motion which the cylinder 13 has to the left of Fig. 5 on its non-sheet taking stroke, and irrespective of any defects in the cam 46.

A fixed cam 48 is provided to open the fingers 32 when the cylinder 13 has traveled to the right of Fig. 1 to permit the sheet to be taken by the delivery mechanism of the machine.

While I have shown and described my novel sheet taking and sheet gaging device as applied to a machine having a reciprocating and rotating cylinder, it will be obvious that many features of my invention may be applied to any kind of a machine having a sheet carrier to which it is desirable to feed sheets accurately and particularly to the ordinary type of printing press in which sheets are fed to a continuously rotating cylinder.

Having now described my invention, what I claim as new and desire to secure by Letters Patent is as follows:

1. A rotating and reciprocating sheet carrying cylinder, sheet grippers thereon, means to support a sheet in a position to be taken

by said sheet grippers, a gage to position the sheet on said supporting means, a projection on said cylinder, a member connected with said gage and arranged to extend in 5 the path of said projection, said member and said projection being constructed and arranged to have yielding contact with each other when said cylinder is moving in one direction, and non-yielding contact when the 10 cylinder is moving in the opposite direction.

2. A rotating and reciprocating sheet carrying cylinder, sheet grippers thereon, means to support a sheet in a position to be taken by said sheet grippers, a gage to position 15 the sheet on said supporting means, a projection on said cylinder, a member connected to said gage and constructed and arranged to be moved by said projection to move said gage when the said cylinder is moving in one 20 direction only.

3. A rotating and reciprocating sheet carrying cylinder, sheet grippers thereon, means to support a sheet in a position to be taken by said sheet grippers, a gage to position 25 the sheet on said supporting means, a projection on said cylinder, a member connected to said gage and constructed and arranged to be moved by said projection to move said gage out of the path of the sheet as it is 30 taken by said sheet grippers, and means to hold said gage out of gaging position.

4. A rotating and reciprocating sheet carrying cylinder, sheet grippers thereon, means to support a sheet in a position to be taken 35 by said sheet grippers, a gage to position the sheet on said supporting means, a projection on said cylinder, a member connected to said gage and constructed and arranged to be moved by said projection to move said 40 gage out of the path of the sheet as it is taken by said sheet grippers, a continuously moving cam shaft and a cam thereon, connected to said gage, and constructed and arranged to hold said gage out of gaging position after said projection has moved out 45 of contact with said member.

5. A reciprocating and rotating sheet carrying cylinder, sheet grippers thereon, a gage to position a sheet to be taken by said grippers, a shaft to support said gage, a member pivoted on said shaft and adjustably connected thereto and constructed and arranged to contact with said cylinder, said member being provided with a yielding device between 50 said shaft and the point of contact with said cylinder, constructed and arranged to permit said cylinder to move said gage when said cylinder is moving in one direction only.

6. A reciprocating and rotating sheet carrying cylinder, sheet grippers thereon, a gage to position a sheet to be taken by said grippers, a shaft to support said gage, a first lever attached to said shaft and a second lever pivoted on said shaft and arranged to 60 contact with said cylinder and to be moved thereby into contact with said first lever when said cylinder is moving in one direction and to be moved away from said first lever when said cylinder is moving in the 65 opposite direction.

7. A reciprocating and rotating sheet carrying cylinder, sheet grippers thereon, a gage to position a sheet to be taken by said grippers, a shaft to support said gage, a first 70 lever attached to said shaft and a second lever pivoted on said shaft and arranged to contact with said cylinder and to be moved thereby into contact with said first lever when said cylinder is moving in one direction and to be moved away from said first 75 lever when said cylinder is moving in the opposite direction, and adjusting means between said levers.

8. A reciprocating and rotating sheet carrying cylinder, sheet grippers thereon, a gage to position a sheet to be taken by said grippers, a shaft to support said gage, a first lever attached to said shaft and a second lever pivoted on said shaft and arranged to 80 contact with said cylinder and to be moved thereby into contact with said first lever when said cylinder is moving in one direction and to be moved away from said first lever when said cylinder is moving in the 85 opposite direction, said second member having a yielding member between said shaft and the point of contact between said second lever and said cylinder.

9. A reciprocating and rotating sheet carrying cylinder, sheet grippers thereon, a gage to position a sheet to be taken by said grippers, a shaft to support said gage, a first lever attached to said shaft and a second lever pivoted on said shaft and arranged to 90 contact with said cylinder and to be moved thereby into contact with said first lever when said cylinder is moving in one direction and to be moved away from said first lever when said cylinder is moving in the 95 opposite direction, and means to hold said gage out of the path of the sheet after said gage has been moved by said cylinder.

RUFUS A. FREEMAN.
